UNITED STATES PATENT OFFICE.

HENRY E. VAN NESS, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,375,870.

Specification of Letters Patent. Patented Apr. 26, 1921.

Application filed March 20, 1919. Serial No. 283,773.

To all whom it may concern:

Be it known that I, HENRY E. VAN NESS, a citizen of the United States, residing at Elmira, in the county of Chemung and State 5 of New York, have invented certain new and useful Improvements in Engine-Starters, of which the following is a specification.

My invention relates to a starter for an engine such as an internal combustion engine and the same pertains more particularly to the drive or transmission of such a starter. For the purpose of a clear and definite description of my invention I have shown and will hereafter describe the same 10 as employed in actual use in connection with the well known Eclipse-Bendix type of drive as exemplified in prior patents issued to Vincent Bendix, for instance, Patents No. 1,125,935, dated January 26, 1915, and No. 20 1,172,864, dated February 22, 1916. This type of drive is characterized by a rotatable member such as a screw shaft operated by a prime mover such as an electric motor and having a driving member such as a pinion 25 mounted thereon and adapted to coöperate with a part, such as the fly wheel, of the engine to be started. This drive is adapted to be operated either directly or indirectly by the motor or if desired the same may be 30 operated by hand.

The object of my invention is to provide simple and efficient means for preventing any creeping of the driving member or screw member on the shaft due more particularly to vibration which causes a slow 35 rotation of the screw member toward the fly wheel or else a slow rotation of the shaft which results in a longitudinal advancement of the screw member toward and against the 40 fly wheel. This creeping movement is liable to occur in certain installations where there is considerable vibration of the engine or where the brushes of the armature do not afford any considerable resistance against 45 this rotation of the armature shaft due to vibration. Referring particularly to the embodiment herein shown, I overcome any possibility of creeping by providing the pinion with a spring wire which extends 50 transversely of the screw shaft in position to coöperate with the latter when the pinion is in its normal or retracted position but to be entirely free thereof after the first initial enforced longitudinal movement of the 55 pinion. The resistance of this spring wire is

such that it prevents said creeping action but does not interfere with the proper operation of the drive. While this anti-creeper device is shown in direct connection with the pinion itself it will be understood that my invention is applicable to a screw member operating on a screw shaft, whether such member be the pinion itself or comprise the operating or controlling means for such a 60 pinion.

In the drawings Figure 1 is a sectional elevation of a starter embodying my invention; Fig. 2 a section on the line 2-2 of Fig. 1; Fig. 3 a sectional elevation of a portion of the drive illustrating a different position 70 of the pinion as compared with Fig. 1; Fig. 4 a section on the line 4-4 of Fig. 3; Fig. 5 a sectional elevation similar to Fig. 3 but showing a further advanced position of the pinion on the screw shaft; Fig. 6 a section 75 on the line 6-6 of Fig. 5; Fig. 7 a sectional bottom plan view of the parts shown in Fig. 5; Fig. 8 a detail section on the line 8-8 of Fig. 7 but on a larger scale; and Fig. 9 a modified form.

In the present instance I have shown my invention as embodied in the Eclipse-Bendix type of drive and I have also shown such drive as direct-driven by an electric motor but it will be understood that my invention 85 is not to be limited thereto but that the same may be embodied in structures of somewhat different character and also that the drive may be indirect-driven and may in fact be 90 operated by hand.

As shown the electric motor A has an extended armature shaft 1 on which is mounted a screw shaft 2 which is in the form of a sleeve and which has at one end the usual screw threads 2^a and at the other end a plain 95 portion except for the provision of a circumferential groove 2^b located intermediate the length of this plain portion. The armature shaft is operatively connected with the screw shaft in the usual way by means of the 100 driving collar 3, bolt 4, coil driving spring 5 and stud 6 screwing into the driving head of the screw shaft. The screw member which is also in itself the pinion 7 is screw-threaded upon the screw shaft and is adapted to move longitudinally thereon and also 105 rotarily therewith. In practice this pinion is provided with a weighted disk 8 whose weight consists of a thickened flange 9.

The anti-creeper device consists of a light 110

spring wire 10 which is mounted upon the screw member or pinion in such way as to be presented to the screw shaft transversely of the axis thereof and in coöperation therewith when the pinion is in its normal or retracted position but to the entirely free therefrom when in the compass of the screw-threaded portion 2^a. As shown, I take advantage of the presence of the weighted disk 10 in the mounting of this spring wire as it affords a convenient means of support therefor with practically no change in the standard type of construction of this drive. In the flange 9 are bored two holes 11 in the same plane and adapted to receive the ends of the wire 10 and permit such wire to rotate. This flange is also cut away slightly at 9^a to accommodate the bent or clenched ends 10^a of the wire. This wire is so positioned on the pinion that normally, that is when straight, it will lie in the bottom of the groove 2^b out of contact therewith.

Describing the operation of my device and starting with the parts in the normal position shown in Fig. 1, when the motor is operated the pinion is advanced longitudinally to the right into mesh with the fly wheel and after the engine has started on its own power the pinion is automatically demeshed and returned to its normal position shown. Upon the initial advancement of the pinion the wire will ride up on the inclined shoulder 2^c of the groove 2^b and onto the plain portion of the shaft adjacent the left hand end of the screw threads. At this time the wire will be slightly flexed as shown in Fig. 4 but the tension is so slight as not to interfere with the enforced longitudinal movement of the pinion that occurs during the regular operation of the drive. The parts now occupy the position shown in Figs. 3 and 4. Upon the continued longitudinal movement of the pinion and when the wire has passed beyond the limits of the plain portion and has entered the limits of the screw threads, it will no longer contact the screw shaft at all but will take its position in the grooves between the screw threads, thereby being absolutely free of the screw shaft after having passed the plain portion thereof. This position of the parts is illustrated in Figs. 5 to 8 wherein the wire is shown as occupying said position in a groove between two screw threads.

Describing the anti-creeper operation and assuming that there is a tendency to advancement of the pinion due to vibration, this tendency is resisted by the wire particularly when upon a slight advancement of the pinion such wire comes into contact with the inclined shoulder 2^c of the groove 2^b which provides a frictional resistance which is of an increasing character until it rides out upon the plain portion of the screw shaft. However, in practice the resistance

caused by the wire in contact with the shoulder 2^c is sufficient to prevent any creeping of the pinion, as in such action the wire will not leave the groove and ride on top of the plain portion of the shaft.

By the use of my invention I provide a very simple, compact and self-contained anti-creeper means for the screw member of a drive or transmission and moreover produce a means of this character which is operative only when the condition in question exists, that is when the screw member is in its normal or retracted position and is inoperative at other times, that is when the pinion is being advanced or retracted longitudinally in the regular operation of the drive, at which time the anti-creeper means has no action whatever upon the pinion or the screw shaft.

These means may therefore be said to co-operate with the screw member at the initiation of its longitudinal movement and to be free therefrom in its further or advanced longitudinal movement. By preference, the wire is out of contact with the screw shaft when the screw member is in its normal or retracted position, so that when the drive is operated for starting, the screw member may have a running start for its longitudinal movement. The actual contact to the wire with the screw shaft therefore occurs in that position intermediate the advanced and the normal positions of the screw member.

In practice, the pinion is placed on a screw 100 stud and the holes 11 are drilled in such position as to permit the wire to pass between the threads of the screw. If desired that the wire should not pass between the threads but press upon the top faces thereof as 105 shown in Fig. 9, then these holes are drilled in another position which, with the same screw shaft and pinion as before described would be at an angle to the first mentioned position.

I claim:

1. In an engine starter, the combination of a rotatable member, a second member mounted thereon for longitudinal movement thereof from a normal position to an advanced position to cause engagement with a part of the engine to be started, and for rotary movement therewith, and means carried by the second member and arranged at the initiation of its longitudinal movement 115 to contact the rotatable member for imparting thereto a yielding resistance but free from such rotatable member in its further longitudinal movement.

2. In an engine starter, the combination 125 of a rotatable member, a second member mounted thereon for longitudinal movement thereof from a normal position to an advanced position to cause engagement with a part of the engine to be started, and for ro- 130

- 5 tary movement therewith, and a spring wire carried by said second member and arranged at the initiation of its longitudinal movement to contact the rotatable member for imparting thereto a yielding resistance but free from such rotatable member in its further longitudinal movement.
- 10 3. In an engine starter, the combination of a rotatable member, a second member mounted thereon for longitudinal movement thereof from a normal position to an advanced position to cause engagement with a part of the engine to be started, and for rotary movement therewith, and a spring wire connected at its ends to the second member and arranged at the initiation of its longitudinal movement to have its central portion contact the rotatable member for imparting thereto a yielding resistance but free from such rotatable member in its further longitudinal movement.
- 15 4. In an engine starter, the combination of a rotatable member, a second member mounted thereon for longitudinal movement thereof from a normal position to an advanced position to cause engagement with a part of the engine to be started, and for rotary movement therewith, and a spring wire mounted at its ends for rotary movement in said second member and arranged to have its central portion coöperate with the rotatable member for imparting thereto a yielding resistance, said wire being adapted to rotate and to yield when said second member in its longitudinal movement reaches a position intermediate normal and advanced positions, and to be thereafter in such advance movement free of the rotatable member.
- 20 5. In an engine starter, the combination of a rotatable member, a second member mounted thereon for longitudinal movement thereof from a normal position to an advanced position to cause engagement with a part of the engine to be started, and for rotary movement therewith, and a spring wire carried by said second member and extending transversely of the rotatable member and in contact therewith only in the position intermediate its normal and its advanced position.
- 25 6. In an engine starter, the combination of a rotatable screw shaft, a screw member screw-threaded thereon, and a spring wire mounted in the screw member and extending transversely of the screw shaft in position to prevent creeping of the screw member on the shaft.
- 30 7. In an engine starter, the combination of a rotatable screw shaft, a screw member screw-threaded thereon, and a spring wire mounted at its ends to rotate in the screw member and having its central portion extending transversely of the screw shaft and adapted to coöperate therewith.
- 35 8. In an engine starter, the combination of a rotatable screw shaft having a threaded portion and an unthreaded portion, a screw member on said threaded portion of the shaft, and a spring wire mounted in the screw member and extending transversely of the screw shaft in position to contact the said unthreaded portion during the initiation of the longitudinal movement of the screw shaft and to lie in the grooves of the said threaded portion and free therefrom when the screw member is further advanced longitudinally of the screw shaft.
- 40 9. In an engine starter, the combination of a rotatable screw shaft having a threaded portion and an unthreaded portion, a screw member on said threaded portion of the shaft, and a spring wire mounted in the screw member and extending transversely of the screw shaft in position to contact the said unthreaded portion during the initiation of the longitudinal movement of the screw shaft and to lie in the grooves of the said threaded portion and free therefrom when the screw member is further advanced longitudinally of the screw shaft.
- 45 10. In an engine starter, the combination of a rotatable screw shaft, a screw member screw-threaded thereon, said screw member having a flanged extension, and a spring wire mounted at its ends in said extension and extending transversely of the screw shaft in position to prevent creeping of the screw member on the shaft.
- 50 11. In an engine starter, the combination of a rotatable screw shaft, a pinion screw-threaded thereon and having a flanged disk at one end, and a spring wire mounted at its ends in the flanges of the disk and extending transversely of the screw shaft in position to prevent creeping of the pinion on the shaft.

HENRY E. VAN NESS.
